(57) **CLAIM**

The ornamental design for a centrifugal separator, as shown and described.

DESCRIPTIONFIG. 1 is perspective view of a centrifugal separator;
FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The broken lines are for the purpose of showing environmental structure and form no part of the claimed design.

1 Claim, 6 Drawing Sheets(56)
